UNITED STATES PATENT OFFICE.

CHARLIE M. MCFARLAND, OF WICHITA FALLS, TEXAS.

AUTOMATIC PUMP.

1,414,990.

Specification of Letters Patent.

Patented May 2, 1922.

Application filed April 13, 1920. Serial No. 373,655.

To all whom it may concern:

Be it known that I, CHARLIE M. MCFARLAND, a citizen of the United States, residing at Wichita Falls, in the county of Wichita, 5 and State of Texas, have invented certain new and useful Improvements in an Automatic Pump; and I do hereby declare the following to be a full, clear, and exact description of the invention, such as will enable 10 others skilled in the art to which it appertains to make and use the same.

This invention relates to an automatic pump, and more particularly to an apparatus designed for pumping oil, and one which 15 may be operated by compressed air supplied from a central air compressor, in order that a number of pumps may be operated from the same source of power.

A further object is to provide a pump, 20 especially adapted for the purpose indicated, but not limited to that use, which will keep the well pumped down to a predetermined level, determined by a float, which automatically sets the pump in operation when 25 the oil or water to be pumped has reached the aforesaid level.

A still further object is to provide a pump 30 from which the paraffine which frequently accumulates in oil pumps may be removed by the simple operation of heating the compressed air by means of which the piston is operated, or by introducing steam into the pump.

A still further object is to provide in connection with a suitable casing and a float 35 operative when the fluid reaches a predetermined level, means for admitting air under pressure for actuating the piston of the pump upon its working stroke, means for automatically returning the piston, and 40 means for controlling the admission and exhaust of the air in timed relation to the movement of the piston.

With the foregoing and other objects in view, the invention consists in the novel construction, combination and arrangement of elements hereinafter described and claimed.

In the accompanying drawings:—

Figure 1 is a vertical section of a pump 50 which is constructed in accordance with my invention.

Figure 2 is a horizontal section on the line 2—2 of Figure 1, looking in the direction indicated by the arrows.

Figure 3 is a vertical section on the line

3—3 of Figure 2, looking in the direction indicated by the arrows.

Figure 4 is a vertical section on the line 4—4 of Figure 2, looking in the direction indicated by the arrows. 60

Figure 5 is a detail view in vertical section of the air cylinder.

Figure 6 is a detail view in vertical section of the lower portion of the discharge pipe, 65 and

Figure 7 is a vertical section through the lower end of a slightly modified form of the pump.

In carrying out my invention, I provide a main casing 10 which is supported by a 70 section of tubing 11. The tubing 11 is suitably mounted, and it houses the supply and discharge pipes 14 and 15 respectively. The pipe 14 conducts air under pressure to the interior of the pump casing, and the oil or 75 other fluid to be pumped is discharged through the pipe 15.

The pipe 14 is under the control of an inlet valve 16 which in turn is under the control of a float 17 and plunger 24. The float 17 is located in a chamber 18 between heads 19 and 20. Near its lower end the float chamber 18 is provided with a fluid inlet and outlet opening 18a. A rod 21 connects the float 17 to one end of the pivoted lever 22, 85 and the other end of the lever is pivotally connected with the stem 23 of the plunger 24, operating in an air cylinder 25. An outlet port 26 for this cylinder communicates with an air exhaust pipe 27. The valve 16 is provided with an operating arm 16a, and this arm is connected by a spring 29 to the upper end of a crank arm 28 on the lever 22. The means connecting the float 17 and 90 plunger 24 to the valve 16 is of such construction that the valve 16 will be closed by and when the float reaches its lowest position as the result of a fall of the liquid in the well below a certain level, that the valve 16 will be closed by and when the float reaches 100 its highest position as the result of the return of the liquid to its normal level, and that the valve will be closed by and when the plunger 24 is forced into its highest position by the air exhausting from the chamber 32. The 105 raising of the float 17 lowers the plunger 24 and the raising of the plunger lowers the float. When the valve 16 is opened by the plunger 24, and when the liquid in the well 110 is at a certain level, the float 17 will be forced

95

110

down into the liquid against its buoyancy. This results in the raising of the float 17 and the opening of the valve 16 after the spent charge of air which opened the valve 16 by 5 raising the plunger 24 has passed out through the exhaust pipe 27. During its upward movement the float 17 swings the arm 28 from the left to the right of the vertical, and during its downward movement the 10 float swings this arm from the right to the left of the vertical. During its upward movement the plunger 24 swings the arm 28 from the right to the left of the vertical. During the movement of the arm 28 from one 15 of its positions to the other the spring 29 is tensioned, and when the arm reaches either of its positions the spring reacts and closes or opens the valve 16 and holds it in the position to which it has been moved.

20 The air inlet pipe 14 is connected at its lower end to a valve casing 30 serving to house a valve 31 which is normally urged in the direction of its seat by a spring 31^a. This valve controls the admission of air into a 25 chamber 32. Within this chamber there is mounted a plunger 33 which has direct connection with the piston 34 by means of a piston rod 35. A spring 36, which encircles the piston rod 35 and which bears its upper 30 end against the under side of the plunger 33 and at its lower end against the upper side of a grid 33^a, returns the elements 33 and 34 to their elevated position after their downward or working stroke.

35 The admission of air under pressure to the chamber 32 forces the plunger 33 and pump piston 34 downwardly, and drives out the oil or other fluid which has entered the cylinder 37 through the intake valve 38 during 40 the upward stroke of the plunger and piston. The fluid passes from the cylinder 37 into the discharge pipe 15. The valve 15' is located as shown and serves the usual purpose. The valve 40 permits the exhaust of air below the plunger 33, in order that the plunger may freely operate on its down stroke. When the plunger 33 and piston 34 reach the limit of their downward or working 45 stroke, the air is exhausted from the upper portion of the chamber 32, the air passing out through a pipe 43 which has communication with the air cylinder 25 in which the plunger 24 operates. The plunger 24 is below the exhaust 26 of the cylinder 25 when 50 the valve 16 is opened, and it is above the exhaust 26 when the valve 16 is closed. An exhaust valve 44 is located at the point shown and controls the passage of air from the upper portion of the chamber 32 into the 55 discharge pipe 43. This valve is normally urged in the direction of its seat by a spring 44^a, and it is in closed position when the valve 31 is in opened position and in opened 60 position when the valve 31 is in closed position. Connected to the upper side of the 65 plunger 33 is a stem 46 having a head 47. The stem passes through an eye portion 48 of a vertically movable rod 49. The rod 49 is slidably mounted in bearings 51 which are carried by a bracket arm 52 depending from 70 the under side of the head 19, and it has sufficient frictional contact with the bearings to prevent it from having any accidental downward movement. A crank arm 52 is carried by the upper end of the rod 49, and secured 75 to the outer end of this arm is a spring 53. The spring is also connected to a crank arm 54 which extends from a cam shaft 55. The cam shaft 55 is journaled in bracket arms 56 which are also carried by the head 19. 80 Cams 57 and 58 are carried by the shaft 55, and they engage the lower ends of the stems 31^b and 44^b of the valves 31 and 44, respectively. The relative arrangement of the cams 57 and 58 is such that when the shaft 85 55 is rocked in one direction the valve 31 is opened and the valve 44 closed. When the shaft 55 is rocked in the reverse direction, the cams 57 and 58 permit the spring 44^a to open the valve 44 and the spring 31^a to close 90 the valve 31.

In the drawings the plunger 33 and the piston 34 are shown at the limit of their up-stroke, the valve 16 is shown in opened position, the valve 31 is shown in opened position, and the valve 44 is shown in closed position. Air under pressure entering the chamber 32 through the valves 16 and 31, forces the plunger 33 and the piston 34 downwardly; that is to say, the air im- 100 parts a working stroke to the piston 34. Just before the plunger 33 and piston 34 reach the limit of their downward or working stroke, the head 47 of the stem 46 engages the eye piece 48, moving the rod 49 downwardly until its crank arm 52 is at a 105 point below the crank arm 54. When the crank arm 52 reaches this position, the spring 53 is under tension and as the result imparts downward movement to the 110 crank arm 54. The oscillation of the shaft 55 as a consequence of this movement of the crank arm 54, moves the cams 57 and 58 in a direction to permit the seating of valve 31 and unseating of valve 44. The air to the 115 chamber 32 is now cut off and communication between the chambers and the air cylinder 25 is established. Air passing from the chamber 32 to the cylinder 25 through the pipe 43, raises the plunger 24. As the plunger 24 is connected to the lever 22 by the 120 stem 23, the upward movement of the plunger will rock the lever 22 against the buoyancy of the float 17, resulting in the closing of the valve 16. When the plunger 24 125 passes upwardly beyond the exhaust port 26, the air in the chamber 32 passes out through the exhaust pipe 27, and the plunger 33 and piston 34 are moved upwardly by the spring 36. Just previous to reaching its highest 130

point, the plunger 33 will engage the enlarged lower end 59 of the rod 49. During the balance of its upward movement, the plunger 33 will move the rod 49 upwardly, and when the plunger reaches the limit of its upward movement the crank arm 52 will be positioned above the crank arm 64, resulting in the tensioning of the spring 53. The spring now moves the crank 54 in the reversed direction, and the oscillation of the shaft 55 as the result of this movement of the crank arm 54 moves the cams 57 and 58 in such a direction as to unseat the valve 31 and seat the valve 44. The instant that the valve 44 is seated, the pressure on the under side of the plunger 17 is less than the buoyancy of the plunger 17, and as the result the plunger will move upwardly and open the valve 16 admitting air to the chamber 32.

20 The pump is adapted to continuously operate as long as there is sufficient oil or other fluid in the well to support the float 17 in its highest position. When the oil or other fluid in the well falls so low as to permit 25 the float to move to its lowest position, the operation of the pump is stopped by the closing of the valve 16. When the oil or other fluid in the well rises sufficiently to return the float 17 to its highest position, the 30 pump is again set in operation by the opening of the valve 16.

In Figure 7 there is illustrated a slightly modified form of the lower end of the pump. In this form, the piston 34 and cylinder 37 are dispensed with, the element 33^a performing the functions of the plunger 33 and the piston 34. In other words, the element 33^a acts as a plunger and piston. It is moved downwardly against the tension of the spring 33^b by air under pressure, and it is moved upwardly by the reaction of the spring 33^b. The preferred form of the invention is especially adapted for use in deep wells, while the modified form is especially adapted for use in shallow wells.

From the foregoing description, taken in connection with the accompanying drawings, it should be apparent that I provide a pump which will automatically and continuously operate as long as the oil or other fluid in the well remains at a certain level, that it will automatically cease to work as soon as the oil or other fluid in the well falls below a certain level, and that it will be again automatically set in operation as soon as the oil or other fluid returns to its first or original level. The pump is simple, durable and efficient, it may be manufactured and sold at a comparatively low cost, and it may 60 be operated at a comparatively low cost.

I have referred to the use of compressed air for driving the plungers downwardly on their working stroke, but do not wish to be

limited to such construction, as the air pressure may be differently applied, and minor 65 details of construction may be changed or altered within the scope of the appended claims.

What is claimed is:—

1. In a pump, a plunger, a throttle valve 70 for compressed air to impart working movement to the plunger, a movable member to control movement of the valve, and a valve to move said member through exhaust of the compressed air from the pump. 75

2. In a pump, a plunger, a throttle valve for compressed air to impart working movement to the plunger, a valve to move the first mentioned valve through exhaust of the compressed air from the pump, a lever connected with one of the valves, and a yieldable connection between said lever and the other valve. 80

3. In a pump, a casing having an air chamber therein, a pump chamber enclosed within the casing, a plunger in said pump chamber, means to return the plungers to inoperative position after the working stroke, means for admitting air under pressure to one side of the plungers for effecting the 85 working stroke, and means for controlling the admission of air and controlling the exhaust of air from the air chamber, said means including a plurality of valves, the 90 position of which is controlled by the position of the plunger, and one of said valves being opened when the other is closed. 95

4. In a pump, an air chamber, a duct for admitting air under pressure thereto, a plurality of valves controlling the passage of 100 air through said duct, a float operatively connected with one of the valves, an exhaust air duct connected with the air chamber, a plunger operated by the exhaust air and having operative connection with the valve 105 last named, a valve controlling the passage of air from the air chamber to the exhaust duct, one of the valves last named being opened when the valve leading from the chamber to the exhaust duct is closed, a 110 plunger in the air chamber, and operated when air is admitted under pressure through the inlet air duct, a pump cylinder and a plunger operating therein, means operatively connecting said plunger, and means operated by the plunger first named for controlling certain of the valves for cutting off the air supply to the air chamber and opening the exhaust duct. 115

In testimony whereof I affix my signature 120 in presence of two witnesses.

CHARLIE M. McFARLAND.
